UNITED STATES PATENT OFFICE.

RALPH E. MARBURY, OF EDGEWOOD PARK, PENNSYLVANIA, ASSIGNOR TO WESTINGHOUSE ELECTRIC & MANUFACTURING COMPANY, A CORPORATION OF PENNSYLVANIA.

VARIABLE CONDENSER.

Application filed December 14, 1920. Serial No. 430,619.

To all whom it may concern:

Be it known that I, RALPH E. MARBURY, a citizen of the United States, and a resident of Edgewood Park, in the county of Allegheny and State of Pennsylvania, have invented a new and useful Improvement in Variable Condensers, of which the following is a specification.

This invention relates to condensers, more especially to variable condensers wherein the capacitance may be regulated at will. Such condensers are particularly adapted for use in wireless-transmission apparatus.

The present invention consists in a modification of the method and structure described and claimed in my copending application, Serial No. 426,969, filed Nov. 29, 1920, for air condensers and method of assembly.

The aforesaid application describes the making of air condensers by assembling a number of plates having alined openings therein on metal spacers or in jigs, passing metal rods through the alined openings in the plates and dipping the assembly in molten solder, whereby a unitary structure is formed. The stationary set of plates is formed with supports at three points and is, therefore, comparatively rigid. The movable set of plates, or rotor, has but a single support on one side thereof and is subject to distortion when force is accidentally applied to the opposite edges of such plates.

The present invention is designed to obviate this difficulty, it being among the objects thereof to provide a structure and a method of assembling the plates of a condenser of the type above set forth which shall render the entire structure more rigid and less expensive to manufacture.

In practicing my invention, I assemble a suitable number of plates alternating with corrugated or crimped washers, and pass a rod or tube through the openings of the assembled plates and washers, and secure the same in position.

More specifically, I provide corrugated washers, the thickness of which is slightly greater than the spaces between the plates in the completed condenser. The washers and plates are assembled and the tube passed therethrough, and a sufficient pressure is applied to the end plates to crush or fold the assembly to the desired thickness.

Since the corrugated washers have very little strength, they readily bend, allowing the plates to assume the correct final position without the use of jigs or spacers. The assembly is then dipped in solder, and, since the surface of the washers is comparatively large, there is a large number of points of contact between the washers and the plates into which the solder flows to form a very rigid unitary structure. Since each plate is supported at a plurality of points at a considerable distance from the central post or tube, the tendency for the plates to bend or twist out of parallel relation is minimized.

In the accompanying drawing forming a part hereof and illustrating a specific embodiment of my invention,

Fig. 1 is an elevational view of a completed condenser constructed in accordance with my invention;

Fig. 2 is a plan view of the movable plate portion or rotor;

Fig. 3 is an elevational view of the same;

Fig. 4 is a plan view of one of the washers utilized in my structure, and

Fig. 5 is an elevational view of the same.

The condenser 1 is formed with upper and lower frame members or plates 2 and 3 of non-conducting material, and a number of spaced supporting posts 4 and 5 are secured therein by suitable means, here shown as threaded ends and nuts. Stationary plates 6 are assembled upon the posts 4 and 5 in any desired manner but preferably by placing a suitable number of such plates in a jig, with openings in alinement, passing posts 4 and 5 through such alined openings and dipping the assembly in molten solder. The stationary part of the condenser so formed is then fixed into the frame of the condenser.

The movable member or rotor 7 of the condenser is formed of a series of plates 8 of suitable shape, preferably a sector of a circle, as a semi-circle, having projecting portions with central openings 9 formed therein. Corrugated washers 10, having openings 11 therein, are assembled alternately with plates 8, the openings 11 and 9 being in alinement. A tube or post 12 is passed through the assembled structure, and pressure is applied to the upper and lower plates to crimp or compress the structure to

the desired shape, giving the correct spacing between adjacent plates 8. A rod 13 is passed through plates 2 and 3 and through tube 12, said tube being secured to rod 13 by set screw 14 or any other suitable means. The rod is then locked into position on the frame by any suitable means, such as lock-nuts 15. A handle 16 of any suitable type is secured to the rod 13 to allow ready manipulation of the rotor.

My improved construction is comparatively inexpensive to manufacture and does not require specially skilled operators. Although I have described the assembling of the rotor by stacking alternately plates 8 and washers 10 and then passing tube 12 therethrough and soldering the same together, it is obvious that details of manipulation may be varied at will. For instance, I may first provide the tube or post 12 and assemble the plates and washers thereon, crimp the same to the final form, and then secure the parts together in any manner, as by soldering, wedging or welding. It is also apparent that various changes in details of the structure of my condenser may be made without departing from the principles thereof. For instance, the corrugated washers may be of any suitable form, the posts 4 and 5 may be mounted in any other manner, and the rotor 7 may be held in the structure by means other than that described above. I may apply the

corrugated washer structure to the stationary portion of the condenser, if desired.

35

I claim as my invention:

1. A condenser comprising spaced plates, corrugated washers interposed between said plates and having aligned openings and a post extending through said openings and holding said plates in their relative positions.

40

2. A condenser comprising spaced plates having aligned openings, corrugated washers interposed between said plates, a tube extending through said openings and holding said plates in their relative positions, and a rod extending through said tube, said rod being pivoted in the frame of said condenser.

45

3. A condenser comprising spaced plates, resilient washers interposed between said plates and having aligned openings and a post extending through said openings and holding said plates in their relative positions with said washers under compression.

50

4. A condenser comprising spaced plane conductor plates of stiff material and corrugated spacers interposed between adjacent condenser plates, said spacers covering only a small part of the surface area of said plates.

55

In testimony whereof, I have hereunto subscribed my name this 30th day of November, 1920.

RALPH E. MARBURY.
